SUPPORT FOR FUR NECKPIECES

Lawrence E. Berglund, Minneapolis, Minn.

Application June 1, 1948, Serial No. 30,269

2 Claims. (Cl. 223—97)

1

This invention relates to a hanger or support for a fur scarf or neckpiece. Such neckpieces are now commonly made from the skin of one or more animals, such as mink, sable, etc. It is a common practice to have a clasp at the end of the scarf formed by the head of the animal and this clasp is usually in the form of a lever pivoted intermediate its ends for vertical swinging movement and being spring pressed to closed position. Said lever usually has a short end which is pressed down with the thumb or finger to open the clasp which is formed by the longer end of the lever.

It is an object of this invention to provide a simple and very efficient device for holding a scarf or neckpiece and by means of which it may be supported.

It is a further object of the invention to provide a hanger for a fur neckpiece, which neckpiece has a clasp comprising a lever pivoted intermediate its ends for swinging movement, said device having a portion adapted to extend around the pivot of said lever, said portion having an upstanding part adapted to engage the side of said lever, said device extending away from said lever and having means at its other end adapted to engage over a support.

It is a further object of the invention to provide a support for a fur neck piece, which neckpiece has a clasp comprising a lever pivoted adjacent one end for vertical swinging movement and spring pressed to urge the other end of said lever downwardly, said device comprising a plate-like member having a recess at one side thereof adjacent one end forming a hook-like portion at said end adapted to extend about said pivot beneath said lever, said device extending in the plane of said lever beneath the same so as to be gripped by the long end of said member and being formed at its other end to engage over a support.

It is more specifically an object of the invention to provide a hanger for a fur neckpiece, which neckpiece has a clasp comprising a swinging lever, said device comprising a plate having a recess in one end so that it can be disposed beneath said lever with the pivot of the lever disposed in said recess, said plate extending away from said lever in tapered form and being transversely bent at its other end to extend over a support.

It is also an object of the invention to provide such a device as set forth in the preceding paragraph, said plate having flanges at one side disposed substantially at right angles thereto adapt-

ed to be disposed at opposite sides of said pivot and engage one side of said lever, the outer of said flanges being elongated and forming a reinforcement.

5 These and other objects and advantages of the invention will be fully set forth in the following description made in connection with the accompanying drawings in which like reference characters refer to similar parts throughout the several views and in which:

Fig. 1 is a front elevational view of the device showing the same in engagement with a neckpiece;

Fig. 2 is a view in side elevation of the device 15 also showing the same in engagement with the neckpiece; and

Fig. 3 is a perspective view of the device.

Referring to the drawing, one end of a fur neckpiece 10 is shown, said end comprising the 20 head 10a of the animal from which the neckpiece is formed. Said neckpiece has a clasp the jaw of which is formed by the snout portion 10b of head 10a. A lever 11 is mounted at the underside of the head 10a substantially centrally 25 thereof transversely and is mounted for swinging movement about a pivot 12 secured in said head portion, said pivot being somewhat closer to the inner end of said lever than to the outer end thereof and being embraced by a spring 13 which tends to move the outer end of said lever against the snout 10b. The clasp can be opened by pressing on the inner end 11a of lever 11 with the thumb or finger. It is a common practice in 30 wearing such a neckpiece to place the same around the neck and engage the neckpiece adjacent the other end in the clasp formed by member 11.

In accordance with the present invention the device 14 is provided and while the same might be variously formed, in the embodiment of the invention illustrated it is shown as formed from a comparatively thin but rigid plate of metal or other material. The main portion 14a of the member 14 is in one plane and has a recess 14b formed therein at one side thus forming a hook-like portion 14c at one end of said member, said portion 14c having its end 14d bent upwardly substantially at a right angle to the plane of portion 14a. A flange 14e is formed along one 45 side of member 14 and extends substantially at right angles to the plane of portion 14a, said flange tapering toward the end of the device opposite the hook portion 14c. The device 14 has means at its upper end to engage over a support 50 and while this could take various forms, in the

embodiment of the invention illustrated plate 14 is reversely curved transversely to have the end hook portion 14f adapted to extend over a rod or other support. Portion 14f is in the same plane as portion 14a.

In operation the member 14 will be held by the upper portion thereof or the portion adjacent the hook portion 14f and the hook portion 14c will be placed around and under the inner end of member 11. The end 11a of member 11 will now be pressed upon and the other end of the lever raised and the member 14 passed under the outer end of member 11 so that portion 14a is now disposed beneath the lever 11 and the hook portion 14c extends about the inner end thereof engaging the pivoted portion of the lever. The upturned portion or flange 14d engages the side of lever 11, as shown in Fig. 1 and the flange 14e also engages the same side of the lever at the opposite side of pivot 12. The member 14 extends away from the scarf substantially in longitudinal alignment with member 11, as shown in Fig. 1, and it can now be hung over a rod 15 or other support in a closet or other location where it is desired to hang the neckpiece. The portion 14a is tightly gripped by the longer end of member 11, and as stated, the flanges 14d and 14e engaging the side of the lever prevent the device from swinging out of alignment with the lever. The pivot 12 and its support is received in the hook 14c and when the side of lever 11 engages the flanges 14e and 14d the scarf cannot move toward the open end of the recess in hook 14c so that the scarf is securely held in position and its weight will insure that it cannot get out of the hook 14c. The flat bottom side of the lever 11 and the flat bottom on the portion 19b of the scarf engage opposite sides of the plate 14 and prevent any twisting action of the scarf. A very secure hold or attachment is thus had by the device on the neckpiece. The device can be very quickly and easily attached to the neckpiece and just as easily and quickly detached.

From the above description it will be seen that I have provided a simple and highly efficient hanger for a fur neckpiece. The device is easily and inexpensively made, the same has been amply demonstrated in actual practice, found to

be very successful and efficient and is being commercially made.

It will of course be understood that various changes may be made in the form, details, arrangement and proportions of the parts, without departing from the scope of applicant's invention, which generally stated, consists in a device capable of carrying out the objects above set forth, in the parts and combinations of parts disclosed and defined in the appended claims.

What is claimed is:

1. A hanger for a fur piece which has a clasp secured thereto comprising a lever oscillatable about a pivot intermediate its ends, said lever and fur piece having flat adjacent sides; said hanger comprising a narrow rigid elongated flat plate disposed in one plane and having a recess therein at one end forming a laterally directed hook at said end, the other end of said plate being formed as a larger hook for supporting said hanger, said plate having a flange along one side thereof intermediate said hooks and a flange along the end of said laterally directed hook, said flanges being disposed substantially at right angles to said plate whereby said pivot and its support can be received in said recess and the side of said lever can engage said flanges to prevent any lateral movement of the fur piece relative to the hanger.
2. The structure set forth in claim 1, said recess or bight in said first mentioned hook being small so as to be adapted to substantially embrace said pivot, the center of said recess or bight in said first mentioned hook being disposed substantially in the longitudinal center line of said plate whereby when said fur piece is suspended on said hanger the longitudinal center line thereof is substantially vertical and in substantial alignment with said center line of said plate.
